2 Claims. (Cl. 123—169)

ABSTRACT OF THE DISCLOSURE

This invention is concerned with an internal combustion engine containing a spark plug with an aurous electrode and an electrical system which is incapable of generating a spark impulse higher than that required by the aurous spark plug.

Background of the invention

This invention relates to the combination of a conventional internal combustion system with an aurous spark plug and an electrical system especially designed to incorporate the economies made possible by the unique characteristics of the aurous spark plug.

The use of spark plugs in conventional internal combustion engines is too well known to require further elaboration. Judicial notice may be taken of the fact that the ignition system in general and the spark plugs in particular are the Achilles heel of modern engines. A new spark plug with sharp clean electrodes and a properly spaced gap will fire readily and reliably with a moderate voltage. However, spark plugs rapidly deteriorate in normal use. The action of the spark tends to erode the metal of the electrodes thereby rounding off sharp edges which inherently produce a high electrostatic gradient and ready ionization of the adjacent air prior to conduction. The same erosion of the metal electrodes increases the gap which must be jumped by the spark. Each of these changes increases the voltage which must be available to the spark plug if the engine is to fire properly. This increase in voltage increases harmfully the energy dissipated in the spark gap.

This combination of circumstances has compelled the use of spark producing electrical apparatus capable of much higher voltages than would be required by new spark plugs so that a reasonable spark plug life can be attained. This expedient is to some extent self defeating as the energy expended in the spark gap increases with increasing voltage thereby increasing the rate of metal erosion and leading to ultimate failure of the spark plug. This failure often occurs when the fouling deposits of carbon and lead salts which are inevitably present provide a shunt path for the sparking current which effectively prevents sparking when the voltage at the spark plug must be elevated to jump the increased gap with rounded electrodes.

Summary

This invention is predicated upon the fact that gold is the only known metal which appears to be completely stable in the metallic state. The substitution of a gold electrode for one of the electrodes in a conventional spark plug appears to halt almost completely the erosive effects mentioned above which tend to round off electrode edges and to increase the spark gap. Even more surprising only one of the electrodes need be fabricated from aurous material. The other electrode may be the familiar nickel base alloys long used as electrodes in spark plugs.

The aurous electrodes need not be pure or fine gold, but may well be alloyed with other metals which tend to decrease the volatility of gold or to raise its melting point. Chromium and palladium are examples of two such

2

metals which may be alloyed with the gold. The gold content should be retained sufficiently high that the peculiar and unique oxidation resistant quality of gold is not substantially impaired. At least one portion of the aurous electrode should have a sharp edge to decrease the potential necessary to produce a spark. The aurous electrode should be supported in intimate thermal contact with a base metal heat sink of sufficient mass and thermal conductivity to prevent undue temperature elevation of the gold.

10 The use of an aurous electrode in an otherwise conventional spark plug prevents the elevation of sparking voltage with use which occurs with the normal base metal electrodes and to a lesser extent with the very special platinum electrode spark plugs. This low and stable sparking potential renders it possible to redesign the electrical system for the production of the sparking impulses so that it is incapable of generating voltages substantially higher than are necessary to fire plugs in the new condition. This makes possible a more economical electrical system to build and one which is more reliable in use. The insulation problems throughout the entire sparking system are far less severe and the current carrying capacity of the contact points may be reduced. Similarly, less difficulty is encountered with very high engine speeds since the energy necessary to adequately charge the spark coil is less.

Brief description of the drawing

The sole figure of drawing is a graphical representation of the voltage at a spark plug necessary to fire the spark plug reliably under a variety of conditions. These tests were conducted with the base metal electrodes and with a spark gap of 0.030 in. The dotted curve labeled "Transient Load Voltage" defines the voltage necessary to reliably fire a spark plug when the throttle is suddenly opened wide. It is this voltage which is meant in the appended claim by the language

"that required to ionize the gas between the electrodes under conditions of maximum pressure in the compression chamber."

The space between this dotted curve and the upper curve which is labelled "Available Voltage" represents voltage ability which need not be built into the system when aurous electrodes are employed.

Description of preferred embodiment

The particular spark plug structure which makes possible the construction claimed herein is produced by altering the construction of the center wire of an otherwise conventional spark plug. The final one quarter to one half inch of the center electrode wire is made by welding securely to the inconel remainder of the center wire a gold wire approximately one sixteenth of an inch in diameter and terminating in a square end. The gap between the squared end of the center wire and the other electrode is set at about 0.030 inch. In such a system, the remainder of the electrical system employed to energize this spark gap may safely be limited to not over 12,000 volts. The actual energy available at the spark gap may well be limited to not over one millijoule and can usually be limited to half this value by virtue of the fixed aurous spark gap.

I claim as my invention:

1. An internal combustion engine comprising a piston, a compression chamber adjacent the end of the piston stroke, means for moving the piston towards the compression chamber to adiabatically compress air into the compression chamber and thereby increase the resistance of such air to ionization, a spark plug in communication with the compression chamber and an electrical system for energizing the spark plug, said spark plug including

a pair of gapped sparking electrodes one of which is fabricated from fine gold or an alloy of fine gold with an amount of non-gold metallic substances in an amount to enhance the resistance of fine gold to melting and evaporation but insufficient to substantially lessen the resistance of fine gold to oxidation under the conditions existing in the compression chamber, said gold electrode including at least one edge of small radius to increase locally the electrostatic gradient tending to ionize the adjacent air, said gold electrode being supported in intimate thermal contact with a thermal sink of sufficient mass and thermal conductivity to limit the temperature reached by the gold electrode, said electrical system including a source of high voltage comprising an iron core and an electrical coil surrounding the iron core and generating a high voltage impulse by a rapid change in the magnetic flux existing in the iron core, said electrical system being characterized by the fact that the energy dissipated in the gap between

the sparking electrodes increases rapidly as the length of the gap increases and being further characterized by the fact that the system providing the high voltage is electrically incapable of generating an electromotive force substantially in excess of that required to ionize the gas between the electrodes under conditions of maximum pressure in the compression chamber.

5 2. The system recited in claim 1 in which the actual electrical energy dissipated in the spark gap is limited to 10 a value not materially in excess of one millijoule.
